UNITED STATES PATENT OFFICE.

DAVID L. SNEDIKER AND JOHN R. GRAHAM, OF EMPORIA, FRANKLIN D. McCOLLUM, OF FLORENCE, KANSAS, AND ISAIAH F. SNEDIKER, OF INDEPENDENCE, MISSOURI.

HEAD-REST.

SPECIFICATION forming part of Letters Patent No. 391,206, dated October 16, 1888.

Application filed November 28, 1887. Serial No. 256,282. (No model.)

To all whom it may concern:

Be it known that we, DAVID L. SNEDIKER and JOHN R. GRAHAM, of Emporia, Lyon county, State of Kansas, FRANKLIN D. McCOLLUM, of Florence, Marion county, State of Kansas, and ISAIAH F. SNEDIKER, of Independence, Jackson county, Missouri, have invented certain new and useful Improvements in Head-Rests, of which the following is a specification, reference being had to the accompanying drawings.

The object of our invention is to produce an improved portable head-rest adapted for attachment to the back of a car or other seat or chair and to support the head and be capable of folding up in compact form for transportation.

Our improvements consist in certain combinations of parts which we will now describe in detail, and then succinctly specify in our appended claim.

In the accompanying drawings, Figure 1 is a front elevation, and Fig. 2 is a side elevation, of our improved head-rest. Fig. 3 is a side elevation of a formal variation of our device, and Fig. 4 is a detail view of a part of the same, showing a set-screw fastening for adjustment of the rest to suit different persons and situations. Fig. 5 shows the form of head-rest illustrated in Figs. 1 and 2 in its folded condition; and Fig. 6 shows the clamp-jaws sprung inward on the cylinder, so as to disconnect them from studs H. Fig. 7 shows a set-screw connection between the cylinder and the supporting-clamp.

Referring particularly to the letters upon Figs. 1 and 2 of the drawings, A indicates a block or cylinder, which may be of wood or any other suitable material, through which pass the two branches of the standard B. This standard is adapted to slide up and down through the holes in the cylinder, so as to lengthen or shorten it to suit different persons and different kinds of seats.

C indicates a rest for the head, hinged or pivoted to the curved ends D of the standard B, which standard may be composed of a single

piece of metal properly bent to form two branches, as illustrated.

E indicates a staple secured to the cylinder, 50 and F a link connected at one end to the staple and at the other end to one of the branches of the standard B, for the purpose of holding the standard in any desired position for adjustment up or down.

F' indicates the clamp adapted to fasten the head-rest to the back of a car-seat, chair, or the like. This may be covered or upholstered in any suitable way. This clamp is composed of a single piece of resilient metal bent so as 60 to form the rings G, surrounding the cylinder, and also the opposite spring jaws of the clamp F'.

H indicates pins or studs fixed in the cylinder, and I indicates a segmental rack secured 65 to the rings G.

The operation of our improved head-rest is as follows: Supposing it to be unfolded, as illustrated in Fig. 1, the standard is adjusted up or down to suit the individual. Then the 70 clamp is secured to the back of a seat, as represented in Fig. 2. In order to adjust the standard and head-rest to the proper inclination, the clamp-jaws may be sprung inward, as indicated in Fig. 6, so as to release the studs 75 H. The standard can then be tilted by turning the cylinder to any desired position, when the clamp-jaws can be released, and they will spring out so that the segmental racks will engage with the studs and hold the standard and 80 head-rest in their adjusted position. By this means we provide a head-rest well adapted for use by travelers upon cars, which is light, cheap, simple, and durable, which can be folded in compact form for transportation, and which 85 can be conveniently applied to use upon the back of any ordinary seat.

In Fig. 3 we show a flat standard B, secured to the cylinder A and to the rest C by means of guide-plates L and set-screws M of usual 90 character, by which all necessary vertical adjustments can be had; but this form is not preferable. Any ordinary means—such, for example, as common set-screws N, (shown in

Fig. 7,)—for connecting and disconnecting the clamp and the cylinder, so that the head-rest can be tilted and adjusted into position and then fixed there, or so that the folding for 5 transportation may be accomplished, can be used instead of the studs and segmental rack shown, our invention not being confined to that particular form of means for connecting and disconnecting the clamp and the cylinder.

What we claim as new is—

The combination of the block or cylinder A, the adjustable standard B, secured thereto, the clamp F', for attaching the rest to a seat, 15 the rings G, secured to the clamp and surrounding the ends of the cylinder, the segmental racks I upon the rings, and the studs H, projecting from the cylinder, so as to engage with the rack, substantially as set forth.

In testimony whereof we have hereunto sub- 20 scribed our names.

DAVID L. SNEDIKER.
JOHN R. GRAHAM.

Witnesses:

O. D. LEE,
EDWIN A. NEWMAN.

In testimony whereof I have hereunto sub- scribed my name.

FRANKLIN D. MCCOLLUM.

Witnesses:
